(57) **CLAIM**

We claim the ornamental design for an electric generator incorporating exhaust heat recovery device, as shown and described.

DESCRIPTION

FIG. 1 is a front perspective view of a first embodiment of an electric generator incorporating exhaust heat recovery device of the present invention;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a first side view thereof;

FIG. 8 is a second side view thereof;

FIG. 9 is an enlarged view of the section denoted by line 9-9 of FIG. 1;

FIG. 10 is an enlarged view of the section denoted by line 10-10 of FIG. 2;

FIG. 11 is a front perspective view of a second embodiment of an electric generator incorporating exhaust heat recovery device of the present invention;

FIG. 12 is a rear perspective view thereof;

FIG. 13 is a front view thereof;

FIG. 14 is a rear view thereof;

FIG. 15 is a top view thereof;

FIG. 16 is a bottom view thereof;

FIG. 17 is a first side view thereof;

FIG. 18 is a second side view thereof;

FIG. 19 is an enlarged view of the section denoted by line 19-19 of FIG. 11; and,

FIG. 20 is an enlarged view of the section denoted by line 20-20 of FIG. 12.

The broken lines shown represent unclaimed subject matter and form no part of the claimed design.
